Henry M. Barnhart INVENTOR,

BY Leggett Leggett

ATTORNEYS.

UNITED STATES PATENT OFFICE.

HENRY M. BARNHART, OF MARION, OHIO.

CAR-UNLOADER.

SPECIFICATION forming part of Letters Patent No. 397,165, dated February 5, 1889.

Application filed July 31, 1888. Serial No. 281,560. (No model.)

To all whom it may concern:

Be it known that I, HENRY M. BARNHART, of Marion, in the county of Marion and State of Ohio, have invented certain new and useful Improvements in Car-Unloaders; and I do hereby declare the following to be a full, clear, and exact description of the invention, such as will enable others skilled in the art to which it pertains to make and use the same.

10 My invention relates to improvements in car-unloaders, in which the plow discharges from the one side of the car, the flat side of the plow being held in place by the stakes along the adjacent side of the car. The plow, at the 15 point thereof, is turned upward, like a sled-runner, to enable the plow to pass from one car to another, even where the cars are of unequal height, the point of plow being also turned laterally away from the guiding-stakes.

20 In the accompanying drawings, Figure 1 is a view in perspective. Fig. 2 is a plan.

A represents a car commonly known as a "flat," and on which the dirt or other material is transported.

25 B represents the plow for unloading material. In many instances the dirt, ballast, or whatever material is being used, is wanted only on the one side of the track. This plow therefore is provided with a mold-board, B', 30 extending obliquely across the car for discharging the load to the one side thereof. The straight side of the plow is provided with a runner, B'', the latter being adapted to fit and travel along the adjacent stakes *a* of the car, 35 by means of which stakes the plow is guided and kept in place during the unloading of the material. The point of the plow curves upward some distance, as shown at *b*, Fig. 1, by means of which the plow is enabled to pass 40 from one car to another without difficulty, al-

though the cars should vary some inches in height. The point of the plow also curves laterally away from the guiding-stakes *a*, as shown at *b'*, Fig. 2, so that there is no danger of the point of the plow colliding with the 45 aforesaid guiding-stakes. A link, C, or other suitable device, is provided for attaching the draft-cable D. The plow is preferably made largely of metal, a suitable frame-work of the same being shown, although such frame-work 50 might be varied indefinitely. The plow may be turned end for end on the car, and consequently the material may be discharged at either side of the track as wanted. From the fact that a side rail heretofore commonly employed for guiding a plow is dispensed with any ordinary car may be used for the purpose, the only preparation necessary being a series of short guiding-stakes, *a*, driven into the sockets, with which latter every flat car 55 is supposed to be provided.

The device is simple and inexpensive, and will be found very effective.

What I claim is—

A car-unloader consisting, essentially, of a 65 mold-board running obliquely across the car for discharging the load to the one side of the car, a runner extending lengthwise of the car for engaging the adjacent side stakes of the car, the point of the plow curving upwardly 70 and curved laterally in the direction away from the adjacent guiding-stakes, substantially as set forth.

In testimony whereof I sign this specification, in the presence of two witnesses, this 75 11th day of April, 1888.

HENRY M. BARNHART.

Witnesses:

JOHN A. WOLFORD,
JOHN F. MCNEAL.
